UNITED STATES PATENT OFFICE.

LARK P. BONEBRAKE, OF MARYVILLE, MISSOURI.

MULTIPLE TERMINAL CUT-OUT.

SPECIFICATION forming part of Letters Patent No. 493,328, dated March 14, 1893.

Application filed November 10, 1892. Serial No. 451,551. (No model.)

To all whom it may concern:

Be it known that I, LARK P. BONEBRAKE, a citizen of the United States of America, residing at Maryville, in the county of Nodaway 5 and State of Missouri, have invented certain new and useful Improvements in Multiple Terminal Cut-Outs, of which the following is a specification, reference being had therein to the accompanying drawing.

10 My invention relates to multiple terminal cut-outs for electric circuits, and has for its object the improvements set forth in the following specification and especially pointed out in the claim.

15 The annexed drawing represents a plan view of my improved cut-out, in which

A indicates a base of any suitable non-conducting material, upon which may be arranged one or more cut-outs, the drawing showing

20 two; but a description of one will answer, as each is a duplicate of the other. Upon the base A are secured metal plates B and C, the plate C being sunk until its face is flush with that of the base, the object of which is to al-

25 low the circuit closer e to bear against the base to prevent its binding upon the pivot, thus securing a free movement. The circuit closer e has its central bearing on a fixed stud k attached to the plate C; to this stud is se-

30 cured the inner end of a volute spring g, the outer end of which is attached to the side of circuit closer e. Upon the end of the circuit closer is secured a contact spring f. When the wires h are fused, the circuit closer will

35 pass from one of the levers d to the other, making contact therewith and closing the circuit through the next succeeding lever d.

The levers d are pivoted to the base at d', and are connected at the opposite end of the 40 fusible ends of the wires h by means of binding screws h', the other end of said wires being attached to the metal plate B in like manner; the levers d are normally held against pins m by the wires h; when in this position

45 their shorter ends form a series of stops and contact points for the circuit closer e, which normally rests against the lever d to the ex-

treme right or left of the series in which position the circuit closers remain until a current of greater intensity than the wires h will 50 carry enters, when the wire in circuit will be fused and lever d having nothing to support it, against the pressure of the circuit closer e, will turn on its pivot d', thus releasing the closer e which is turned by the spring g until 55 it makes contact with the next lever d of the series, thus establishing the circuit through the second lever of the series. In this way the circuit can be re-established automatically after each interruption, until all the 60 wires h have been burned out.

My improvement consists in pivoting the levers d on a circular line so that all the levers d are of one length, making a uniform tension on wires h when the circuit closer is 65 in contact; also in providing the stops or pins m to prevent the levers from being displaced before the wires h are fused; and in pivoting the levers d and circuit closer e flush with the base A, which prevents lateral motion and 70 consequent binding upon the pivots; and spring f on the end of circuit closer e to insure perfect contact with lever d.

I am aware that it is not new to provide a series of contact points connected with the 75 main line by fusible wires and a spring impelled circuit closer, and I therefore lay no claim to such structure broadly.

What I do claim as new, and desire to secure by Letters Patent, is—

80 A multiple terminal cut-out, consisting of a series of contact levers pivoted on a circular line and held to position by a series of pins and fusible wires, the latter connecting with the main line, in combination with a spring 85 actuated circuit closer pivoted concentric to said contact levers, and spring on the end of the circuit closer, substantially as described.

In testimony whereof I affix my signature in presence of two witnesses.

LARK P. BONEBRAKE.
